UNITED STATES PATENT OFFICE.

MELVIN S. LOWER, OF BARBERTON, OHIO, ASSIGNOR TO SUN RUBBER COMPANY, A CORPORATION OF OHIO.

TIP FOR HYDROMETER SYRINGES.

Application filed November 8, 1926. Serial No. 147,175.

A type of hydrometer syringe that has long been in common use is that in which the rubber tip has at one end a stopper-like plug that fits into the glass jar of the device. The plug must of course, fit tightly to prevent leakage past the same and to prevent the tip from dropping off. While this type of tip is in other ways an excellent one, difficulty has always been experienced in securing a plug that may be applied readily to the jar and thereafter remain in place. The plug is usually tapered rather sharply toward a rib or flange extending around the same at the juncture of the same with the spout, so that the compression of the plug increases progressively from the smaller end toward the base as the plug is forced into the jar. Jars of the same kind vary somewhat in diameter and it is therefore impossible so to design the plug that the rib or flange thereon will always abut against the end of the jar when the plug is forced into the latter. The result is that, even though the plug is pushed in with considerable force, the large end of the plug usually projects beyond the end of the jar, producing an abrupt bulge, as it were, in the plug. At the juncture of the bulge with the compressed portion in the jar the rubber is under compression in the direction of the length of the plug and therefore tends to pull the plug out.

The object of the present invention is to produce a plug for a tip or nozzle or the like in which the objections to the old type will be overcome and which may easily be applied to a barrel or tube and will fit snugly into and be securely held in the latter.

In carrying out my invention I so shape the plug that all radial compression thereof occurs while the rib or flange is still at some distance from the end of the jar when the plug is forced into the latter. Thereafter there is only frictional resistance to further inward movement of the plug and, because this is much less than the resistance encountered while compression is taking place, the last portion of the movement of the plug is a quick jump or snap which brings the rib or flange into contact with the end of the jar. When the plug is once in place there are no internal forces tending to force it out and it remains securely attached to the

jar. I attain this improved result by forming a groove around the base of the plug, adjacent to the rib or flange, or, viewed in another way, by reducing the size of the plug at the base to form a neck. Thus, when the plug is pushed into a jar, its entire effective length is compressed and then a portion smaller in diameter than the interior of the barrel enters the barrel, no further compression resulting.

Not only does the presence of a neck at the inner end of the plug do away with objectionable internal stresses in the plug when attached to a jar, but I have found that the excessive taper heretofore employed in an endeavor to make the plug stick is unnecessary; and therefore less effort is required to force the plug into the jar.

The various features of novelty whereby my invention is characterized will herein-after be pointed out with particularity in the claim; but, for a full understanding of my invention and of its objects and advantages, reference may be had to the following detailed description taken in connection with the accompanying drawing, wherein:

Figure 1 is an elevation of my improved tip attached to a jar or tube of which only a fragment is shown; Fig. 2 is a longitudinal axial section through the parts shown in Fig. 1; and Fig. 3 is a side elevation and Fig. 4 a plan view of the tip removed from the jar or tube.

Referring to the drawing, 1 represents a spout or nozzle enlarged at one end to form a head 2. Beyond the head is a plug 3 slightly smaller in diameter at its free end than at the base; the largest diameter of the plug being much less than that of the head, whereby the head forms a rib or flange around the plug. The base of the plug is spaced apart a short distance from the head, being connected thereto by a neck 4 whose diameter is preferably less than the smallest diameter of the plug or, at least, smaller than the internal diameter of the jar or the like with which the plug is to be associated. Or, if the entire part of the tip beyond the head is referred to as the plug, the plug may be said to have a groove extending around the same at the juncture of the plug with the rib or flange constituted by the marginal portions of the head.

The plug is fitted into the end of a jar or

- tube, such as shown at A in Figs. 1 and 2, the rib or flange abutting against the extreme end of the jar. As best shown in Fig. 2, the short neck at the base of the plug 5 is not in contact with the surrounding jar and is not subject to radial compression. Therefore, after the plug proper has passed into the jar, the resistance that had been encountered because of the need to decrease 10 the diameter of the plug to allow it to enter the jar suddenly ceases and the tip jumps forward until brought to rest through the engagement of the flange or rib with the end of the jar.
- 15 When the parts are assembled, as shown in Figs. 1 and 2, the reacting forces between the plug and the jar are all radial, there being none in the longitudinal direction. Consequently the grip of the jar upon the 20 plug is all utilized to support the weight of the tip and any load that the tip may be carrying, no part thereof being required to counteract internal stresses in the tip. A grooved plug need therefore have only a

slight taper to insure the permanency of its 25 connection with the jar.

While I have illustrated and described with particularity only a single preferred form of my invention, I do not desire to be limited to the exact structural details thus 30 illustrated and described; but intend to cover all forms and arrangements which come within the definitions of my invention constituting the appended claim.

I claim:

A rubber tip adapted to be attached to the end of a tubular member, comprising an element having at one end a tapered plug to be forced into said member and an enlargement inwardly of said plug to abut 40 against the end of said member when the plug is inserted in the same, and there being between the plug and said enlargement a short section of smaller diameter than the interior of said tube.

In testimony whereof, I sign this specification.

MELVIN S. LOWER.
